[57] CLAIM

The ornamental design for a pencil cup, as shown and described.

DESCRIPTION

FIG. 1 is a front elevational view of a pencil cup showing my new design;

FIG. 2 is a rear elevational view thereof;

FIG. 3 is a top plan view thereof;

FIG. 4 is a bottom plan view thereof;

FIG. 5 is a right side elevational view, the left side

elevational view being a mirror image thereof; and

FIG. 6 is a top, right front perspective view thereof.

FIG 1

FIG 2

FIG 3

FIG 4

FIG 5

FIG 6
